ADJUSTABLE CURTAIN ROD

Ralph Blake, Newark, N. J.

Application February 9, 1948, Serial No. 7,041

2 Claims. (Cl. 211—105.6)

1

This invention relates to improvements in adjustable rods and more particularly to improvements in adjustable rods adapted to the support of window curtains and the like.

Highly variable window dimensions in buildings has long made an adjustable curtain support a necessity but the adjustable supports available at present are relatively fragile by virtue of the adjustable means and require brackets for attaching the rod to the top of the window.

It is an object of the instant invention to provide an adjustable curtain rod of substantial rigidity.

A further object is to provide a curtain rod that is minutely adjustable over relatively wide limits.

Still another object is to provide an adjustable curtain rod capable of being supported by the adjusting means.

Other objects of the present invention will become apparent in the course of the following specification.

In the accomplishment of these objectives, the adjustable curtain rod is formed of a hollow cylindrical body portion having a broadly adjustable member in one end and a minutely adjustable spring tension member in the other end. By making the adjustable curtain rod of sufficient overall minimum length to fit the narrowest of a selected series of windows of varying width, the broadly adjustable member is designed to be withdrawn from the rod until the overall length is slightly greater than that of the selected window. Then, by inserting the end of the broadly adjustable member against one of the uprights of the window frame, the curtain rod is rotated upwardly against the other upright member which forces the minutely adjustable spring member within the hollow cylindrical body portion under sufficient tension to maintain the curtain rod horizontal under the weight of the curtain. By the use of components designed for rigidity, the adjustable curtain rod has been found to be capable of supporting a curtain of relatively heavy weight without distortion. Held in place by the minutely adjustable spring tension member, no brackets for supporting the rod are required readily adapting the same for use around

2

masonry and materially decreasing the usual work involved in removing and hanging curtains.

The invention will appear more clearly from the following detailed description when taken in connection with the accompanying drawing showing by way of example a preferred embodiment of the invention.

In the drawings:

Figure 1 is a top plan view of the adjustable curtain rod constructed in accordance with the principles of this invention.

Figure 2 is a sectional view along the line 2—2 of Figure 1, enlarged.

Figure 3 is a sectional view along the line 3—3 of Figure 1, also enlarged.

Figure 4 is a sectional view along the line 4—4 of Figure 2, further enlarged.

Figure 5 is a sectional view along the line 5—5 of Figure 3, likewise enlarged.

Referring now in greater detail to the drawings in which like reference numerals indicate like parts, reference numeral 10 (Fig. 1) indicates the adjustable curtain rod, 11 the hollow cylindrical body portion, 12 (Fig. 2) the broadly adjustable member; and 13 (Fig. 3) the minutely adjustable spring tension member.

The hollow cylindrical body portion 11 may be formed of any suitable material with an inside diameter sufficient for insertion of the subsequently described concentric rod 14 (Figs. 2 and 3) as well as the broadly adjustable member 12 and the minutely adjustable spring tension member 13. The outside diameter of the hollow cylindrical body portion 11 will vary with the span and the load to be supported.

The concentric rod 14 is non-rotatably inserted within the hollow cylindrical body portion 11 in such a manner as to leave a space between the ends thereof and the ends of the hollow cylindrical body portion 11 for insertion of the later described broadly adjustable member 12 and the minutely adjustable spring tension member 13 as shown in Figures 2 and 3.

One end 14a of the concentric rod 14 is of reduced diameter having along the top and bottom surface portions thereof the spaced notches 15, 15a, 15b, 15c, 15d, and 15e. While the notches are shown in spaced and opposed relationship along the top and bottom surface portions 17 of the end 14a with undisturbed surface portions of

the end 14a therebetween, notches exclusively at the top or bottom might be used dependent upon the type of co-acting prongs 19 and 20 (Fig. 2) on the end of the broadly adjustable member 12 and later described. At the opposite end of the concentric rod 14 is a pin 16 for maintaining in position the subsequently described spring member 18 on the minutely adjustable spring tension member 13.

The broadly adjustable member 12 (Fig. 2) is at least a partially hollow tube having an outside diameter for slidable and rotatable insertion in the open end of the hollow cylindrical body portion 11 (Fig. 2) opposite the end 14a of the concentric rod 14. The inside diameter of the broadly adjustable member 12 is sufficient for slidable and rotatable movement over the notched end 14a of the concentric rod 14, previously mentioned. At the end of the broadly adjustable member 12 are the prongs 19 and 20 which are formed of such shape and with sufficient tension to enter the notches 15, 15a, 15b, 15c, 15d, and 15e when the broadly adjustable member 12 is rotatably and longitudinally moved over the notched end 14a. When the broadly adjustable member 12 is rotated either clockwise or counterclockwise 90° from the position in which the prongs 19 and 20 are in any set of opposed notches, such as 15a and 15d shown in Figure 2, the prongs 19 and 20 are forced out of the opposed notches 15a and 15d onto the outside surface portion of the notched end 14a and in which position the broadly adjustable member 12 may be moved longitudinally along the notched end 14a until the substantially desired overall length of the curtain rod 10 is attained. Then, a rotary motion of some 90° again applied to the broadly adjustable member 12 will tend to force the prongs 19 and 20 into another set of opposed notches.

In the opposite end of the hollow cylindrical body portion 11 is the minutely adjustable spring tension member 13 which may be in the form of a rod on the end of which the tip 21 (Fig. 3) is disposed and having an outside diameter sufficient to be slidable in the end of the hollow cylindrical body portion 11. The coiled spring 18 is inserted between the tip 16 of the concentric rod 14 and the tip 21 of the minutely adjustable spring tension member 13 so that when the overall length of the rod 10 is slightly greater than the distance between two vertical members intended to support the curtain rod 10, it will be held in place by the action of the spring 18.

In the free ends of both adjustable members 12 and 13 are the tips 22 and 23 which are formed of the vertical end members 22b and 23b integral with or otherwise attached to the perpendicular members 22a and 23a of sufficient diameter for insertion in the ends of the adjustable members 12 and 13. The tips 22 and 23 may be made of rubber and provide substantial gripping or friction surfaces for the curtain rod 10. While the curtain rod 10 could be used without the tips 22 and 23, the use of such devices has been found expedient where the upright supports for the curtain rod 10 are highly glazed masonry or the like.

The operation is as follows:

The adjustable curtain rod 10 is held roughly and horizontally across the selected window in the hand to estimate the probable adjustment required for mounting the rod. Having determined, for example, that the required adjustment is greater than that provided for by the adjustable spring tension member 13, the broadly adjustable

member 12 is rotated some 90° which releases the prongs 19 and 20 from the notches 15a and 15d (Fig. 2) making the member 12 slidable over the notched end 14a of the concentric rod 14. The broadly adjustable member 12 is then pulled out of the end of the hollow cylindrical body portion until the approximate width is attained and again rotated, clockwise or counterclockwise, 90° which, probably with slightly more longitudinal adjustment, locks the prongs 19 and 20 into another set, such as 15 and 15e (Fig. 2), of opposed notches. The tip 22 is then placed roughly at the desired point of erection on one of the vertical members, and the opposite end of the curtain rod 10 having the minutely adjustable spring tension member 13 rotated upwardly until the tip 23 is against the opposite vertical support under tension. Leveling is attained merely by pushing or pulling on one end of the curtain rod 10 while the curtain may be attached before or after the rod is erected.

It is apparent that the specific illustrations shown have been given by way of illustration and not by way of limitation and that the structure above described is subject to a wide variation and modification without departing from the scope or intent of the invention, all of which variations and modifications are to be included within the scope of the present invention.

What is claimed is:

1. An adjustable curtain rod comprising a hollow cylindrical body portion, a concentric rod of substantially shorter length inserted in the hollow cylindrical body portion and adapted to leave a space at both ends, at least one end of the concentric rod having a substantially smaller diameter than the inside diameter of the hollow cylindrical body portion, at least one notch formed on the outside surface portion of the end of the concentric rod having the smaller diameter; the adjustable curtain rod further comprising a substantially hollow tubular member with an inside diameter greater than the outside diameter of the notched end of the concentric rod and adapted for insertion in the end of the hollow cylindrical body portion, at least one prong on the end of the hollow tubular member and adapted to engage the notch when the tubular member is rotated about and moved longitudinally along the notched end of the concentric rod.

2. An adjustable curtain rod comprising a hollow cylindrical body portion, a concentric rod disposed within the hollow cylindrical body portion and adapted to leave a space between the ends of the concentric rod and the ends of the hollow cylindrical body portion, a tip disposed on one end of the concentric rod, the opposite end of the concentric rod having a substantially smaller diameter than the inside diameter of the hollow cylindrical body portion, a plurality of spaced opposed notches formed on the outside surface portion of the end of the concentric rod of smaller diameter; the adjustable curtain rod further comprising a substantially hollow tubular member slidably and rotatably disposed in one end of the hollow body portion and over the end of the concentric rod of smaller diameter, at least one prong on the hollow tubular member co-acting with the opposed notches and adapted to engage the same under compression as the hollow tubular member is rotated and moved longitudinally over the end of the concentric rod of smaller diameter; the adjustable curtain rod further comprising a coiled spring disposed in

the opposite end of the hollow cylindrical body portion over the tip on the end of the concentric rod, an adjustable spring compression member comprising a rod slidably disposed in the opposite end of the hollow cylindrical body portion against the end of the coiled spring, a tip disposed on the end of the rod and adapted to be inserted in the outside end of the coiled spring; and friction surfaces disposed on the free ends of the broadly adjustable member and minutely adjustable spring compression member in a plane substantially perpendicular to the longitudinal center lines thereof.
